VERSATILE VISE JAW

Clair R. Kinney, Redwood City, Calif.

Application July 19, 1950, Serial No. 174,730

1 Claim. (Cl. 81—38)

1

This invention relates to work holders, and more particularly to face plates or covers for vise jaws.

The object of the invention is to provide a novel means for detachably mounting face plates or covers of a relatively soft material upon the jaws of a vise or other work holder, so that work pieces will not be marred or otherwise damaged by the pressure of the jaws thereon.

Another object of the invention is to provide means for mounting various face plates on jaws of vises, whereby the metal jaws of a conventional vise will be covered with a relatively soft or flexible material, so that the work being held will not be scratched or marred.

A further object of the invention is to provide face plates which are extremely simple and inexpensive to manufacture.

Other objects and advantages will be apparent during the course of the following description.

In the accompanying drawings forming a part of this application, and in which like numerals are used to designate like parts throughout the same:

Figure 1 is a fragmentary side elevational view showing the cover of the present invention applied to the jaws of a vise;

Figure 2 is a perspective view of one of the mounting magnets;

Figure 3 is a front elevational view of a modified cover;

Figure 4 is a top plan view of the cover of Figure 3, showing a flexible sheet attached to the face plate;

Figure 5 is an elevation of the flexible sheet and shows the sheet detached from the face plate of Figure 4;

Figure 6 is a side elevational view of another modified cover;

Figure 7 is a front elevational view of still another modified cover;

Figure 8 is a sectional view taken through the assembly of Figure 7;

Figure 9 is a front elevational view of still another modified cover;

Figure 10 is a side elevational view, with parts broken away and in section, showing the cover of Figure 7 applied to the jaws of a C-clamp;

Figure 11 is a fragmentary side elevational view of a vise jaw with another modified cover applied thereto;

Figure 12 is a view similar to Figure 11, but showing another modified cover;

Figures 13, 14 and 15 are sectional views illus-

2

trating different ways of connecting the magnet to the face plate.

Referring in detail to Figures 1 and 2 of the drawings, the numeral 20 designates a conventional work holder, such as a vise, the work holder 20 including a slide 21, a fixed jaw 22, and a movable jaw 23, there being an operating handle or lever 24 for moving the jaw 23. The jaws 22 and 23 are metal, and each of these jaws is provided with opposing faces 25, Figure 1.

The present invention is directed to a cover and means for mounting such a cover on each of the metal jaws of a work holder or vise, so that a work piece being clamped between these jaws will not be scratched, marred or otherwise damaged by the pressure of the jaws. The cover of Figure 1 is indicated generally by the numeral 26, and the cover assembly 26 includes a rectangular block 27 which is fabricated of a relatively soft material, such as wood. Arranged contiguous to one side of the block 27 is a magnet of the permanent type, and the magnet is indicated by the numeral 28. The magnet 28 has a substantially L shape, and includes a horizontally disposed ledge 29 which overlies the upper surface of the proper jaw 22 or 23 so as to provide an additional supporting means for the cover assembly.

Thus, when the cover assembly of the present invention is being used, the magnet 28 is arranged as shown in Figure 1, so that this magnet is contiguous to the face 25 of the jaw 22 or 23. Due to the magnetism in the member 28, this magnet 28 will maintain the wood block 27 connected to the vise jaw 22 or 23.

For connecting the magnet 28 to the wood block 27, the magnet 28 is provided with a plurality of spaced openings or apertures 30, Figure 2. Suitable securing elements, such as screws 31, extend through the countersunk openings 30 and into the block 27 for maintaining the magnet and block in assembled relation.

Projecting from one side of the block 27 is a plurality of grommets or studs 32, and these studs 32 provide an anchoring means for a flexible sheet of felt, rubber, or leather, whenever such sheet is desired or required as an additional protective cover for the blocks 27.

Referring to Figure 3, there is shown a slightly modified cover which is indicated generally by the numeral 33. The cover assembly 33 again includes the rectangular wood block 27 which is provided with the plurality of studs or grommets 32. However, in Figure 3, a rectangular, flat mag-

net 34 is secured to the block 27 by screws 31,

and the magnet 34 is used in lieu of the magnet 28, but these magnets serve the same purpose.

Referring to Figures 4 and 5 of the drawings, it will be seen that a flexible sheet of felt, rubber, or leather is provided, and this sheet is designated by the numeral 35. The sheet 35 provides an additional protecting cover for the block 27, so as to insure that this block does not scratch or otherwise mar work pieces which are being clamped between the jaws. For connecting the sheet 35 to the block 27, one end of the sheet 35 is provided with a pair of spaced apertures 36, Figure 5, and certain of the studs or grommets 32 extend through these apertures 36 in order to anchor one end of the sheet 35 to the block 27. The other end of the sheet 35 is provided with openings 37, and coil springs 38 each have an end arranged in engagement with the openings 37. A ring 39 is arranged on the other or free end of each of the coil springs 38, and the rings 39 are adapted to be arranged in engagement with other of the grommets or studs 32, whereby the sheet 35 will be maintained stretched across the work-engaging face of the block 27.

Referring to Figure 6, there is shown another modified cover for application to the jaws of a vise or work holder, the cover of Figure 6 being indicated generally by the numeral 40. The cover assembly 40 includes the wood block 27, and arranged contiguous to one face of the block 27 is a piece of steel, aluminum or iron which is indicated by the numeral 41. This piece of material 41 may be secured to the wood block 27 in any suitable manner, as by rivets or screws. The piece 41 has a substantial L shape and includes a ledge 19 which overhangs or overlies the vise jaw when the cover assembly 40 is being used, and this ledge 42 serves to prevent tilting of slipping of the cover assembly 40. If desired, one of the flexible sheets 35 can be wrapped around the wood block 27. Secured to the piece 41 is the flat bar magnet 34, and the magnet 34 again serves to provide a means for detachably connecting the cover assembly 40 to the proper metal jaw of the work holder.

Referring to Figures 7, 8 and 10, there is shown another modified cover assembly for attachment to or application to the jaws of a work holder, such as a C-clamp 46. The cover assembly of Figures 7, 8 and 10 is designated generally by the numeral 42, and includes a block 43 which may be circular or cylindrical in shape. The block 43 may be fabricated of wood, rubber or other soft material. Arranged contiguous to one face of the block 43 is a cylindrical magnet 44, and the magnet 44 is secured to the block by any suitable securing element, such as the screw 45.

The C-clamp 46 is conventional and includes a movable jaw 48 which is actuated by a screw member 49, and the C-clamp further includes a fixed jaw 47. One of the cover assemblies 42 may be detachably connected to each of the metal jaws 47 and 48, so that work pieces can be clamped between these jaws without damaging or otherwise marring such work pieces. Thus, as shown in Figure 10, the fixed jaw 47 has the magnet 44 of one of the cover assemblies 42 arranged contiguous thereto, while the other jaw 48 also has a cover assembly 42 detachably connected thereto.

In Figure 9, there is shown a slightly modified cover assembly which is indicated generally by the numeral 50, and the cover assembly 50 includes a rectangular block 51 which may be fabricated of any suitable soft material, such as wood

or rubber. Arranged contiguous to one face of the block 51 is a rectangular magnet 52, the magnet 52 being connected to the block 51 by suitable securing elements, such as the screw 45. The cover assembly 50 is used in the same manner as the cover assembly 42 previously described.

Referring to Figure 11, there is shown another modification of the cover for attachment to a vise jaw, such as the vise jaw 22. The cover of Figure 11 is indicated generally by the numeral 53, and includes a magnet 54 which is adapted to be positioned contiguous to the face 25 of the jaw 22. The magnet 54 is secured to a strip 55 by any suitable securing elements. The strip 55 may be of any suitable material, such as copper, brass, aluminum, or other soft metal or material.

In Figures 13, 14 and 15, there are shown several different ways for connecting the magnet 54 and strip 55 together. Thus, in Figure 13, rivets 56 connect the magnet 54 and strip 55 together, while in Figure 14, screws 57 are used for connecting these members together. In Figure 15, bolt-and-nut assemblies 58 are used to connect the strip 55 to the magnet 54.

Referring to Figure 12, there is shown a further modified cover which is designated generally by the numeral 60. Cover 60 includes an L-shaped magnet 61 which is adapted to have its upper, horizontal portion or leg 63 overlie the vise jaw 22, so as to prevent slipping or tilting of the cover 60. A suitable L-shaped strip 62 is secured to the magnet 61 by suitable securing elements, and the strip 62 may be fabricated of any suitable soft material, such as copper, brass, aluminum or any other soft material.

From the foregoing, it is apparent that a cover or face plate, as well as a novel means for mounting such face plates on the jaws of vises or other work holders have been provided. Thus, in Figures 1 and 2, the blocks 27 or face plates 27 are detachably connected to the opposing faces 25 of the jaws 22 and 23 by means of the magnet 28. Thus, finished work pieces, or any work piece, can be clamped between the jaws 22 and 23 without any danger of these work pieces being scarred or otherwise damaged by the metal jaws 22 and 23. Also, if desired, the flexible sheet of belt, rubber or leather 35 shown in Figures 4 and 5 can be extended around the face plate or wood block 27 so as to provide an additional soft covering to prevent scratching of the work piece clamped in the vise or other work holder.

In Figures 7 through 10, there is shown cover assemblies for use on work holders, such as a C-clamp 46. The blocks or face plates 43 which are fabricated of wood, rubber or other soft material, again serve to prevent the work piece from being scratched or otherwise damaged.

The cover assembly of the present invention is simple and inexpensive to manufacture, and may be quickly and easily attached to any ordinary metal vise jaw, whereby such a vise can be converted into a woodworking vise, whereby wood pieces or other soft work pieces will not be scratched while being held in the vise. The magnets of the various cover assemblies hold the face plates or blocks in their proper positions until the work piece is clamped by the vise. Then, the pressure of the vise holds the face plate and work securely. The magnets may be of any shape desired, as previously described in this application. The covers of the present invention can be easily attached to and detached from any ordinary metal-jaw vise. Metal jaws will be converted so that they can be used by

persons engaged in woodworking as well as persons in the plastics, leather and other allied fields. Also, the cover assemblies can be tilted, if desired, and due to the provision of the magnets, the covers will remain immobile in their tilted positions. The cover assemblies of the present invention will save space in shops, since they will eliminate the need for two types of vises, and when the covers are not being used, they may be easily removed and conveniently stored. The cover assemblies shown in Figures 11 and 12 are particularly useful for machinists who are engaged in metal working operations which require that the jaws of the vise have a smooth surface. Thus, the cover assemblies of Figures 11 and 12 provide a smooth surface for the jaws and also provide a surface that is slightly softer than the metal or material being worked. The strips 55 in Figures 13, 14 and 15 can be removed and replaced as desired. The cover 50 of Figure 9 can be used for "pony" clamps, if desired. The magnets maintain the face plates in place while the clamp or vise is being adjusted and tightened, and when the vise is tight, the pressure of the jaws will maintain the face plates in proper position.

I claim:

In a cover assembly for the metal jaw of a

work holder, a block, a plurality of spaced parallel studs extending from one side of said block, a magnet secured to said one side of the block and adapted to be arranged contiguous to the metal jaw, a flexible sheet extending around the other side of said block and provided with a plurality of apertures for engagement with certain of said studs, there being a plurality of openings arranged in the other end of said sheet, coil springs each having an end arranged in engagement with said openings, and a ring arranged on the free end of each of said coil springs for engagement with certain of said studs.

CLAIR R. KINNEY.
